F. L. ALSOBROOK.

WATER HEATER.

APPLICATION FILED APR. 9, 1918.

1,275,193.

Patented Aug. 13, 1918.

UNITED STATES PATENT OFFICE.

FRANCIS L. ALSO BROOK, OF ALAMO, TENNESSEE.

WATER-HEATER.

1,275,193.

Specification of Letters Patent. Patented Aug. 13, 1918.

Application filed April 9, 1918. Serial No. 227,478.

To all whom it may concern:

Be it known that I, FRANCIS L. ALSO BROOK, a citizen of the United States, residing at Alamo, in the county of Crockett and State of Tennessee, have invented or discovered certain new and useful Improvements in Water-Heaters, of which the following is a specification, reference being had therein to the accompanying drawing.

10 This invention relates to a water heater suitable for army or other camp use, and has for its object to provide a convenient device of this sort which comprises certain removable parts which may be taken down 15 for convenient transportation. To this end the device comprises a stove which may be of conical or upwardly tapering form and which will preferably be of sheet metal and adapted to burn wood; although the invention 20 may be applied to a stove adapted to consume any kind of fuel, either solid, liquid or gaseous. The water heater proper consists of an annular vessel adapted to be supported on the upper part of the stove, which 25 latter may be provided with a removable smoke pipe. The water heating vessel is furnished with a suitable cover which may be lifted when access to the chamber of the vessel is desired, and such cover is preferably 30 provided with a spring-acted retaining device which will hold the cover in place to close the said water heating vessel, or which device will retain the cover in lifted position on the smoke pipe when access to the 35 water heating vessel is desired.

In the accompanying drawing Figure 1 is a sectional elevation of a preferred embodiment of the invention, and Fig. 2 is a plan view, partly in horizontal section, on the line 40 2-2, Fig. 1, of the same.

Referring to the drawing, 12 denotes a stove, which may be of sheet metal or other suitable material. This stove is preferably provided with an upper door 13 to permit 45 combustible material to be supplied to the stove, and a lower door 14 which may be opened for the removal of ashes, or for permitting a suitable draft. The doors 13 and 14 may, if desired, be provided with draft 50 openings 15, adapted to be closed by suitable slides.

Supported at the upper part of the stove 12 is an annular water heating vessel 16 rather closely fitting the upper conical part 55 of the stove 12. A tapering sleeve or thimble 17 will, however, preferably be inter-

posed between the upper part of the inner wall of the vessel 16 and the stove for the purpose of steadyng the said vessel on the stove without requiring it to be wedged too tightly against said stove. The sleeve or thimble 17 is preferably wedge-shaped, in vertical section, being thickest at its top. The smoke pipe 18 is preferably fitted to the upper part of the stove 12, said smoke-pipe 65 preferably resting on said sleeve or thimble.

The cover 19 of the vessel 16 is preferably provided with a spring-pressed holding device by which said cover may be retained in place to close said vessel, or by which said 70 cover may be held in an elevated position on the smoke pipe 18 when access to the said vessel is desired. To this end the cover is provided with upwardly projecting lugs 20 in which is mounted a sliding bolt 21 having a fixed collar 22^a carrying a knob 22 and between which collar and one of said projections is located a spiral spring 23 serving to press said bolt inward. The bolt 21 carries at its inner end a curved member 24 80 adapted to fit against the smoke pipe 18 and thus frictionally retain the cover in position to close the vessel 16, when desired; or this spring-acted retaining device may be utilized to hold the cover in lifted position 85 on the smoke pipe, as denoted by dotted lines in Fig. 1, when access to the vessel is desired.

From the foregoing it will be understood that the invention provides a simple water 90 heating device consisting of certain removable parts which may be readily assembled, and which can be quickly taken apart for convenient transportation. It will be understood that the stove 12 may or may not be 95 provided with supporting legs 25. If it be open at its bottom, and thus adapted to rest directly on the ground, no legs will be required.

The water heating vessel 16 will prefer- 100 ably be provided with a faucet 26.

Having thus described my invention, I claim and desire to secure by Letters Patent:

1. The combination with a suitable stove, of an annular water heating vessel support- 105 ed thereon, a smoke pipe fitted to the upper part of said stove, said vessel having a removable cover provided with a spring-pressed retaining device acting against said smoke pipe and thus serving to frictionally 110 retain said cover in position, to close said vessel, or to hold said cover in an elevated

position on said smoke pipe when access to said vessel is desired.

2. The combination with a suitable stove, of an annular water heating vessel supported thereon, a smoke pipe fitted to the upper part of said stove, said vessel having a removable cover provided with a spring-pressed retaining device acting against said smoke pipe and thus serving to frictionally retain said cover in position to close said vessel, or to hold said cover in an elevated position on said smoke pipe when access to said vessel is desired, said retaining device comprising a spring-pressed sliding bolt having at its inner end a curved member adapted to fit against said smoke pipe.

3. The combination with an upwardly tapering stove, of an annular water heating vessel supported on the tapered upper part thereof, a smoke pipe fitted to the upper part

of said stove, and a tapering sleeve or thimble interposed between the said vessel and said stove.

4. The combination with an upwardly tapering stove, of an annular water heating vessel supported on the tapered upper part thereof, a smoke pipe fitted to the upper part of said stove, said vessel having a removable cover provided with a spring-pressed retaining device acting against said smoke pipe and thus serving to frictionally retain said cover in position, to close said vessel, or to hold said cover in an elevated position on said smoke pipe when access to said vessel is desired.

In testimony whereof I affix my signature.

FRANCIS L. ALSO BROOK.
